Application filed March 24, 1890. Serial No. 345,162. Term of patent 3½ years.

To all whom it may concern:

Be it known that we, EDWARD L. TORSCH and JAMES R. LEE, citizens of the United States, residing in Baltimore city and State 5 of Maryland, have invented and produced a new and original Design for the Ornamentation of Badges, of which the following is a specification, reference being had to the accompanying drawing, forming part thereof, 10 in which the figure is a face view of a badge showing our design.

The leading feature of the design consists in the central figure A, which includes the triangular side figures B B' and the upper and 15 lower shield-like figures C C'. The figure B to the left includes the representation within a circle of the well-known Grand Army star, while the figure B' to the right includes the representation in a circle of the coat of arms of the State of Massachusetts. The lower 20 shield figure C' has representations of vertical bars, while the upper shield figure includes the representation of short bars and also a field containing the representation of stars. Above the figure A is produced an 25 apron or curtain like representation D, while below such figure is produced a fringe-like representation E, having an inverted-V-shaped lower edge.

What we claim is—

The design for a badge herein shown and 30 described.

EDWARD L. TORSCH.
